UNITED STATES PATENT OFFICE.

HORACE G. KNOWLES, OF WILMINGTON, DELAWARE.

DESIGN FOR A HAND-TRUCK.

SPECIFICATION forming part of Design No. 31,647, dated October 10, 1899.

Application filed August 26, 1899. Serial No. 728,629. Term of patent 14 years.

To all whom it may concern:

Be it known that I, HORACE G. KNOWLES, a citizen of the United States, residing at Wilmington, in the county of New Castle and State of Delaware, have invented and produced a new and original Design for Hand-Trucks; and I do hereby declare the following to be a full, clear, and exact description of the same, reference being had to the accompanying drawings, forming a part thereof.

This invention relates to a new and original design for hand-trucks; and it consists in the peculiar shape hereinafter described, and shown in the accompanying drawings.

15 In the accompanying drawings I have shown the truck in perspective view in Figure 1 and in side elevation in Fig. 2.

The essential characteristics of the design as shown in the drawings consist of the bar 20 A, having a curved upper end terminating in a handle *a* and having a forked lower end B. The extremities of the forked branches have

upturned portions C. At the opposite sides of the arms are wheels, their location being shown.

25 Substantially midway of the length of the bar A is the laterally-extended bar D, the same being curved upwardly, and extends in opposite directions from the bar A.

The essential feature of the design resides 30 in the shape of the bar A with the associated rest and the parallel arms at the lower end of the bar, substantially as shown.

Having thus described my invention, what I claim as new, and desire to secure by Letters 35 Patent, is—

The design for a hand-truck, substantially as shown and described.

In testimony whereof I affix my signature in presence of two witnesses.

HORACE G. KNOWLES.
